W. J. CUMMINGS,
AUTOMATIC GAS RELEASE PACKER,
APPLICATION FILED FEB. 20, 1922.

1,412,275.

Patented Apr. 11, 1922.

UNITED STATES PATENT OFFICE.

WILLIAM J. CUMMINGS, OF BRECKENRIDGE, TEXAS.

AUTOMATIC GAS-RELEASE PACKER.

1,412,275.

Specification of Letters Patent. Patented Apr. 11, 1922.

Application filed February 20, 1922. Serial No. 537,823.

To all whom it may concern:

Be it known that I, WILLIAM J. CUMMINGS, a citizen of the United States, residing at Breckenridge, in the county of Stephens and State of Texas, have invented certain new and useful Improvements in Automatic Gas-Release Packers, of which the following is a specification.

My invention relates to gas release packers and valves therefor; and the object is to provide releasing devices by which a constant pressure can be exerted on the upward flowing liquid by releasing a part of the pressure below the packer and the amount of pressure to be released can be regulated by spring-controlled valves. The object is to prevent too much pressure on the gas or oil producing sands and to provide simple means for controlling and regulating the upward flow of liquid and gas and to prevent too free passage of the gas, so that the gas can be efficiently utilized for lifting the oil out of the wells. Other objects and advantages will be fully explained in the following description and the invention will be more particularly pointed out in the claims.

Reference is had to the accompanying drawings which form a part of this application.

Fig. 1 is a side elevation of a release packer. Fig. 2 is an enlarged vertical section, the valves being omitted. Fig. 3 is an enlarged vertical section of one of the valve casings. Fig. 4 is a plan view of the valve.

Similar characters of reference are used to indicate the same parts throughout the several views.

The packer includes a block 1, preferably of cylindrical rubber which has a central opening for the passage of an oil or other liquid discharge pipe 2. Compression rings 3 and 4 are mounted on the upper and lower ends of the packer 1. Means are provided for expanding the packer against the casing wall 5. A cone-shaped coupling 6 receives the upper end of the discharge pipe 2 and this pipe is supported in the coupling 6 by a collar 7. The coupling 6 has the upper end threaded interiorly for coupling to the discharge pipe (not shown). A similar expanding coupling may be used in the lower end of the packer, as indicated by dotted outline 8. Pipes 9 are provided for

escape of gas and these pipes are inserted in the packer.

Collars 10 hold the pipes 9 in place to prevent these pipes from coming out of the packer. Nuts 11 may be screwed on the lower end of the pipes 9 for compressing the rings 3 and 4 on the packer 1 for expanding the packer against the casing 5. The tapering end of the coupling 6 will be forced by the weight of the pipes downwardly and the rubber of the packer 1 will be expanded against the walls of the casing 5, or against the wall of the well.

The gas is held below the packer to assist in elevating or ejecting the oil or other liquid. The pipes 9 are provided with valves 12 which are inclosed in casings 13. The casings 13 are provided with seats 14 through which the gas passes. The valve 12 is provided with a conical tip for closing or partly closing the passage through the seat 14. A spiral spring 15 is used to hold the valve 12 down to a predetermined pressure. A perforated cap 16 is screwed on the casing 13. An elongated nut 17 is screwed on the pipe 9 and also screwed into the cap 16 to form an upper seat for the spring 15. The pressure is determined by screwing the nut 17 more or less down into the cap 16 to compress the spring 15 more or less so that the gas will have to press more or less on the valve 12 to pass out the pipe 9. The seat in the valve 12 is formed at 18 in the top of the wings of the valve.

The valve spring 15 may be set to resist five pounds pressure or any pressure required. The object is to prevent too much pressure being thrown on the gas or oil producing sands and to provide means by which a constant pressure can be exerted for discharging oil or other liquid. The gas will pass upwardly through the pipe 2 for aiding in discharging the oil or other liquid. The concave packer rings 3 and 4 will hold the packer securely in place. If the gas pressure becomes too great below the packer, the valves 12 will let the gas pass through the pipes 9 until the pressure below the packer is released.

What I claim, is,

1. A gas release packer comprising a cylindrical block of resilient material having an opening vertically therethrough, a discharge pipe passing through said opening, compressor packer rings inclosing the

2.
ends of said block, a cone-shaped coupling for expanding said block against a well casting, and gas release valves and pipes running from said valves through said block for escape of gas.

2. A gas release packer comprising a block of compressible and resilient material having an opening vertically therethrough, a discharge pipe extending through said opening, a cone-shaped coupling for expanding said block against the walls of the well casting, gas escape pipes projected through said block, and pressure gauged valves for controlling the passage of gas through said gas escape pipes.

3. A gas release packer comprising a block of compressible and resilient material provided with an opening vertically therethrough for a discharge pipe, means for ex-

panding said block against the walls of well, 20 gas release pipes projected through said block, and spring gauge valves for said release pipes to control the passage of gas therethrough.

4. A gas release packer comprising a block 25 of compressible and resilient material provided with an opening vertically therethrough for a discharge pipe, means for expanding said block against the walls of a well, compressor rings on the ends of said block, gas release pipes projected through said block and through said rings, and spring gauge valves on the lower ends of said release pipes for controlling the amount of pressure to be retained below said packer. 35

In testimony whereof, I set my hand, this 1st day of February, 1922.

WILLIAM J. CUMMINGS.
